UNITED STATES PATENT OFFICE.

SYLVESTER O. GOULD, OF MARION, INDIANA.

ENGINE.

1,129,086.

Specification of Letters Patent. Patented Feb. 23, 1915.

Application filed July 29, 1911. Serial No. 641,284.

To all whom it may concern:

Be it known that I, SYLVESTER O. GOULD, a citizen of the United States, residing at Marion, in the county of Grant and State 5 of Indiana, have invented a new and useful Engine, of which the following is a specification.

It is the object of the present invention to provide an engine having a single cylinder, in which a pair of pistons operate, under the impulse of fluid-pressure delivered between them, to secure the rotation of a single drive shaft, a novel form of valve mechanism being provided, and novel means being included whereby a dead center will be overcome.

A further object of the invention is to improve generally, devices of the type to which the invention appertains, and to increase the 20 efficiency of an engine of the type herein disclosed.

With the foregoing and other objects in view which will appear as the description proceeds, the invention resides in the combination and arrangement of parts and in the details of construction hereinafter described and claimed, it being understood that changes in the precise embodiment of invention herein disclosed can be made 30 within the scope of what is claimed without departing from the spirit of the invention.

In the accompanying drawings,—Figure 1 shows the invention in longitudinal section, parts appearing in elevation; Fig. 2 35 is a side elevation; Fig. 3 is a sectional elevation at right angles to the showing of Fig. 1; and Fig. 4 is an elevation at right angles to the showing of Fig. 2, and depicting an opposite side of the engine from that 40 appearing in Fig. 3.

In carrying out the invention there is provided a cylinder 1, open at both ends, and jacketed, as shown at 2, the cylinder 1 being formed, preferably, integrally with a base 3, 45 to which the crank case 4 is secured. The jacket 2 is formed at one side with a combustion chamber 5.

Mounted for reciprocation in the cylinder 1, are pistons 6 and 7, the piston 6 being operatively connected with the pitman 8, pivoted to one end of a walking beam 9, fulcrumed intermediate its ends, as shown at 10, upon a standard 11, fashioned upon any suitable or accessible portion of the engine 55 structure.

To the outer end of the walking beam 9,

is pivoted the upper end of an upright connecting rod 12, the lower end of which is pivoted to one arm of a bell crank 14, fulcrumed upon a shaft 15, carried by the base 3. The other arm of the bell crank 14 is pivotally united with a horizontally disposed connecting rod 16, operatively connected with a crank 17, fashioned in a crank shaft 18, journaled for rotation in mating 60 bearings 19, formed in the base 3 and in the crank case 4, the shaft 18 carrying the fly wheel 20, and constituting the drive shaft of the engine. A pitman 21 is also operatively connected with the crank 17, the upper end 65 of the pitman 21 being connected with the piston 7.

To the crank shaft 18 is secured a pinion 22, meshing into a larger gear wheel 23, secured to a cam shaft 24, journaled for rotation in the base 3.

The shaft 24 carries a pair of spaced cams 25 and 26, angularly disposed with respect to each other, as clearly shown in Fig. 1. The cam 25 is adapted to engage one end of 70 a lever 27, which is fulcrumed adjacent its outer end, as shown at 28, in the base 3. The cam 26 is adapted to engage a similar lever 29, as Fig. 3 will show. The lever 27 is adapted to engage an upright plunger 30, 75 and the lever 29 is adapted to engage an upright plunger 31, the plungers 30 and 31 being slidably mounted in bosses 32, formed in the base 3.

The plungers 30 and 31 are adapted to 80 bear against heads 33, formed upon the ends of valve stems 34 and 35, slidably mounted in the lower portion of the combustion chamber 5, the plunger 30 serving to actuate the stem 34, and the plunger 31 serving to 85 actuate the stem 35. The stem 34 carries a valve 36, and the stem 35 carries a valve 37, adapted to register in seats 38, formed in a transverse portion 39, located within the combustion chamber 5, the combustion 90 chamber, above the partition, communicating with the interior of the cylinder 1, as shown at 40. Compression springs 44 surround the valve stems 34 and 35, the springs 44 bearing at their upper ends against the lower face of the combustion chamber 5, the lower ends of the springs bearing against the heads 33. The action of the 95 springs 44, therefore, is to maintain the valves 36 and 37 seated.

Mounted in the upper portion of the combustion chamber 5, or in any other desired

section thereof, is a spark plug 41 or like device having the same function. In one side of the combustion chamber 5 there is, below the partition 39, an inlet port 42, an oppositely disposed exhaust port 43 being located in the opposite side of the combustion chamber.

Presupposing that the parts are positioned as shown in Fig. 1, the operation of the device is as follows: When the charge is exploded between the pistons 6 and 7, the pistons will be forced apart in opposite directions. The piston 6, through the instrumentality of the pitman 8, will tilt the walking beam 9 upon its fulcrum 10, the walking beam 9, by means of the connecting rod 12, tilting the bell crank 14, the bell crank operating the connecting rod 16, and the connecting rod 16, through the medium of the crank 17, causing a rotation of the shaft 18. When the piston descends, the pitman 21 will actuate the crank 17, and aid in the rotation of the shaft 18. Thus, both the pistons 6 and 7 will operate to turn the shaft 18. In Fig. 1, the pitman 21 is shown as being upon dead center, but it will be seen that the bell crank 14 is so positioned, that the operation of the piston 6 will serve to prevent a dead centering of the engine as an entity, the connecting rod 16 and the pitman 21 never being upon dead centers, at the same time. When the pistons 6 and 7 separate, in the manner hereinbefore described, the pinion 22, meshing into the gear wheel 23, will cause a rotation of the cam shaft 24, the cam 25, in the first instance, engaging the lever 27, and raising the plunger 30, the plunger 30 elevating the valve stem 34, and unseating the valve 36, whereupon the pistons 6 and 7, as they separate, will draw inwardly through the inlet port 42, the explosive mixture. By the time that the pistons 6 and 7 start to approach each other, the valve 36 will have closed, and the ap-

proaching pistons will connote and compress the explosive charge between them, which charge will be exploded, when the pistons have secured a proper compression. The expanding charge will separate the pistons 6 and 7, and when the pistons again approach each other, the cam 26 will actuate the lever 29, raising the plunger 31, and operating the stem 35, effecting an unseating of the valve 37, the exploded charge being forced outwardly, through the exhaust port 43.

Having thus described the invention, what is claimed is:—

In a device of the class described, a shaft having a plurality of cams; levers fulcrumed at their outer ends; a slidably mounted pin bearing upon each lever between the fulcrum of the lever and the cams; and a valve actuated by each pin; each cam including a curved lifting edge and an edge disposed radially of the shaft, the extreme inner end of each lever being adapted to traverse the lifting edge of one cam, and to drop abruptly to the rear of the radial edge thereof thereby to effect a sudden release of the corresponding pins, the radial edge of one cam being spaced from the lifting edge of the next cam by a surface concentric with the shaft, upon which surface the extreme ends of the levers are adapted to ride between the dropping of the inner ends of the levers and the raising thereof, without raising the inner ends of the levers, thereby permitting the pin to drop into engagement with the levers before the inner ends of the levers are raised.

In testimony that I claim the foregoing as my own, I have hereto affixed my signature in the presence of two witnesses.

SYLVESTER O. GOULD.
